[57] **ABSTRACT**

This invention relates to a closure cap for inspection holes in the walls of housings of tool and fabrication machines, vehicles and the like. In particular for land and sea vehicles there is the desire to close holes in the housing or in the body with a closure cap, said holes serving an inspection of some parts or having to be accessible only occasionally for other reasons, said closure cap permitting a ready attachment and releasing again also without any particular difficulties, but on the other hand at least dustproof, if possible even spray-waterproof closing the hole in the wall. This closure cap is to also be able to be made in a simple and economical way, since it is to be removed and applied again by less skilled persons also depending on circumstances, and is to be formed simple and sturdy and is to be easy to handle.

CLOSURE CAP FOR INSPECTION HOLES

SUMMARY OF THE INVENTION

For the foregoing reasons screw caps cannot be considered having threads which can easily be damaged just as well as other closure caps cannot be considered having complicated closure means.

The simple plugs also used some times, which are merely pressed into the holes and are retained therein by friction or also by elastically projecting lugs are not suited for the purposes under consideration here, since they on the one hand tend to drop out in case of vibrations like they occur in machines as well as in vehicles and because they on the other hand are difficult to apply or to be released again, in particular for big holes, in case a sealing closure is desired.

An object of the invention therefore is to provide a simple and effective closure cap for inspection holes, which can at any time and without any difficulties be released and applied again, sealingly, but which on the other hand does not have the disadvantages of the cited conventional closure caps.

According to the invention it is provided for that the closure cap includes a generally disc-shaped base body provided with a central bore and superimposing the margins of the wall opening with its margin as well as a spider-shaped lock body inserted in the base body and rotatable relative thereto of a soft resilient material, in particular plastic. The base body is capable of being inserted in the opening and has an annulus provided with a plurality of passages, while the lock body includes a collar capable of being inserted in the central bore of the base body one or more engaging surfaces for a tool for retaining the lock body and integral fingers projecting outwardly from this collar. These fingers are offset respectively along a portion of their length, all in the same rotational sense, a portion of their length extending inclined relative to the radius passing through its junction with the collar. The free ends of these fingers respectively extend into the said passages in the annulus of the base body.

In case this closure cap is to be inserted in an inspection hole, the lock body is rotated in the one rotational direction by applying a tool to the engaging surfaces provided for this purpose in such a way that the ends of the fingers are positioned within the annulus of the base body. Then the base body is inserted with its annulus in the wall opening until the outer margin tightly and sealingly abuts the margins of the opening. Then the lock body is rotated relative to the base body in the opposite direction. Thereby the ends of the fingers forcedly are shifted through the passages in the annulus of the base body outwardly and engage underneath the margin of the wall opening and thereby unlooseably retain the closure cap, since between the finger ends on the one hand and the superimposed margin of the base body on the other hand an according spacing is provided.

Although preferably such closure bodies are required for circular wall openings, it is expressively emphasized that the invention also includes closure caps for openings formed in a geometrically different way, for instance square openings.

The number of the fingers of the lock body depends on the shape and size of the closure cap as well as other requirements differing from case to case.

The engaging surfaces provided for applying a tool for retaining the lock body are preferably defined by a non-circular configuration of the recess of the collar. Preferably the collar is closed by a wall formed integral therewith, and the non-circular recess is disposed within this wall.

In order to prevent a dropping out of the lock body for instance as a result of vibrations, in a further development of the invention it is proposed that the collar of the lock body is provided at its free end at the outside with an annular bead. This annular bead is first of all resiliently compressed in radial direction when applying the collar in the central opening of the base body and then snaps resiliently outwardly after inserting the collar and engages behind the margin of the central opening of the base body.

In order to enhance the retaining effect of the fingers of the lock body, it is furthermore proposed that the ends of the fingers are formed enlarged relative to the central portions thereof. The central portions themselves will be formed comparatively thin in order to facilitate an according deformation of the fingers when rotating the lock body.

In order to furthermore prevent that the ends of the fingers when rotating the lock body in its releasing position slide entirely out of the passages in the annulus of the base body in case of an unskilled use and later do not find back into these holes when rotating it into the lock position, it is provided according to the invention to arrange a web extending generally radially inwardly from the annulus thereof to the proximity of the central aperture within the base body adjacent to each passage, the web with a surface thereof facing the adjacent passage serving as a guide surface for the end of the finger of the lock body disposed there. These guide surfaces directly guide the finger end into the passage in the annulus of the base body when the lock body is rotated.

In order to on the other hand prevent a too great rotation of the lock body into the releasing position, in a further development of the invention it is provided for that noses are arranged at the fingers in the vicinity of their junctions with the collar, but opposite to the direction of the fingers themselves, said noses engaging the web located there in case of a retrograde rotation of the lock body after a predetermined angular rotation, thereby limiting the rotation of the lock body in a releasing direction.

According lock noses can also be provided for limiting the rotation of the lock body in the locking direction, in particular at the ends of the fingers.

In order to accomplish a particularly satisfactory sealing and at the same time a resilient retaining arrangement, it is furthermore proposed that the outer margin of the base body superimposing the wall opening is formed tapered lip-like and converging to the wall surface at a flat angle and that the base body is formed in one piece of a soft resilient material, in particular plastic.

BRIEF DESCRIPTION OF THE DRAWINGS

The invention is explained in closer detail hereinafter in referring to an embodiment on the basis of the drawing. Therein:

FIG. 1 is a bottom view of the closure cap according to this invention;

FIG. 2 is a bottom view of the base body;
 FIG. 3 is a sectional view along line III—III of FIG. 2;
 FIG. 4 is a top view of the lock body; and
 FIG. 5 is a sectional view along line V—V of FIG. 4.

DESCRIPTION OF THE PREFERRED EMBODIMENT

The base body 1 in particular illustrated in FIGS. 2 and 3 is generally formed disc-shaped and is provided with a central bore 2. It is of such a large size that its outer margin 3 superimposes the margins of the wall opening. On the bottom side an annulus 4 is integrally connected to the base body made of plastic, which has a plurality of circumferentially spaced passages 5.

Adjacent each passage in counter-clockwise direction a web 13 extends away from the annulus 4 generally radially inwardly to the proximity of the central bore 2. The surface 14 adjacent to each passage 5 of this web serves as a guide surface for the fingers of the lock body, as will be set forth hereinafter.

The spider-shaped lock body 6 likewise made of soft resilient plastic has been illustrated individually in FIGS. 4 and 5. It includes a collar 7 and offset fingers 8 integrally in setting out therefrom, the ends 9 of which are thickened and are dimensioned in such a way that they can easily be pushed through the said passages 5 of the base body 1.

At the junction of the fingers with the collar 7 these are even thinner than at their central portion so that they are hinge-like pivoted to said collar 7. In the vicinity of the pivot junction a short nose 15 extends away from each finger 8 in opposite direction.

At its free end the collar 7 at the outside carries an annular bead 12 which tapers outwardly toward the free end.

At the other axial end the collar 7 is closed by a wall 10 in which a slot 11 is provided for accepting a screwdriver.

In FIG. 1 the closure cap combined of two parts has been illustrated in a bottom view. The spider-shaped lock member 6 is positioned in the base body 1, the collar 7 extending through the central bore 2 and projecting with its annular bead 12 beyond the top side of the base body in the vicinity of the central bore, a fact which cannot be recognized in FIG. 1. This bead 12 has been pressed through the central bore in a resilient compression and has been recoiled outwardly again so that the lock body 6 is retained unlooseably, but freely rotatable in the base body.

In the position illustrated in FIG. 1 of the closure cap the ends 9 of the individual fingers are in the passages 5 of the base body 1, but do not project beyond the periphery of the annular portion 4 of the base body.

If the collar 7 of the lock body 6 is rotated, however, in a counter-clockwise direction (in FIG. 1), the outer ends 9 of the fingers 8 forcedly are moved radially outwardly and thereby project beyond the periphery of the annulus 4 of the base body 1. In this position they engage behind the margin of the opening in the wall and retain it tightly seated therein. For this rotational movement the surfaces 14 of the individual webs 13 which are closely disposed adjacent to the respective passage

5 in the annulus 4 of the base body serve as guide surfaces for the ends 9 of the fingers and reliably guide these finger ends into the passage, as has been stated before.

5 When the collar 7 of the annular body is turned back again in the clock-wise direction into the releasing position illustrated in FIG. 1, however, an over-turning is prevented by the noses 15 at the junctions of the fingers 8, since these noses abut the webs 13 of the adjacent web.

10 I claim:

1. Closure cap for inspection holes in the walls of housings and the like, characterized by a generally disc-shaped base body 1 provided with a central bore 2 and superimposing the margins of the wall opening with its

15 margin 3, said base body having an annulus 4 capable of being inserted in the opening and provided with a plurality of passages 5, as well as by a spider-shaped lock body 6 inserted in the base body and rotatable relative thereto of a soft resilient material, in particular plastic, which includes a collar 7 insertable in the central bore 2 of the base body 1, one or more engaging surfaces for a tool and fingers 8 integrally projecting outwardly from said collar, said fingers each extending over a portion of their length inclined relative to the radius through their junction with the collar, all fingers being offset in the same rotational sense and the free ends 9 of said fingers respectively extending into the

20 passages 5 in the annulus of the base body.

25 2. Closure cap according to claim 1, characterized in that the engaging surfaces at the collar of the lock body are defined by a noncircular configuration of the recess of the collar.

30 3. Closure cap according to claim 2, characterized in that the nonround recess 11 is provided in a wall 10 closing the collar and formed integral therewith.

35 4. Closure cap according to claim 3, characterized in that the collar 7 of the lock body is provided at its free end outwardly with an annular bead 12 for an unlooseable attachment to the base body.

40 5. Closure cap according to claim 1, characterized in that the ends 9 of the fingers are formed widened relative to the central portions thereof.

45 6. Closure cap according to claim 1, characterized by webs 13 arranged generally star-like within the base body adjacent each passage and extending from the ring thereof inwardly to the vicinity of the central opening, the surfaces 14 of said webs facing the passages 5 in the annulus of the lock body serving as guide surfaces for the ends 9 of said fingers.

50 7. Closure cap according to claim 6, characterized by noses 15 projecting from the fingers in the vicinity of their junctions with the collar opposite to the direction of these fingers for limiting the rotation of the lock body in releasing direction.

55 8. Closure cap according to claim 7, characterized in that the outer margin 3 of the base body superimposing the wall opening is formed lip-shaped tapered and converging toward the wall surface at a flat angle and the base body is made in one piece of a soft resilient material, in particular plastic.
